UNITED STATES PATENT OFFICE.

NORBERT KOCH, OF ESSEN-RELLINGHAUSEN, GERMANY, ASSIGNOR TO FRIED. KRUPP AKTIENGESELLSCHAFT, OF ESSEN-ON-THE-RUHR, GERMANY.

RECOIL-GUN ON WHEELED GUN-CARRIAGE.

1,156,533.

Specification of Letters Patent.

Patented Oct. 12, 1915.

Application filed July 3, 1913. Serial No. 777,257.

To all whom it may concern:

Be it known that I, NORBERT KOCH, residing at Essen-Rellinghausen, Germany, a subject of the Emperor of Germany, have invented a certain new and useful Improvement 5 in Recoil-Guns on Wheeled Gun-Carriages, of which the following is a specification.

This invention relates to recoil guns on 10 wheeled gun carriages which are intended for firing against air ships. It has heretofore been customary in guns of this kind either to make provision for swinging the whole gun carriage easily and within certain 15 wide limits, (as for instance by swinging the carriage wheels into a position in which the carriage can be trained by means of these wheels; or by means of special foundations or other devices). Or else the carriage has been constructed so that the trail sides may be spread apart, that means brought outside of the path of the recoiling gun. Besides the intricate construction, gun carriages of this kind have the 20 disadvantage, that they cannot be quickly put in action after the unlimbering and at the end of the firing will not be very rapidly made ready for transportation.

The object of this invention is now to 25 provide a recoil gun on a wheeled carriage, which is suitable for firing against air ships and possesses a greater field of elevation and azimuth, and which does not have the disadvantages above mentioned.

In the accompanying drawing one embodiment of the invention is illustrated and Figure 1 shows a side elevation partly in section of the gun carriage with the gun in horizontal position; and Fig. 2 a top plan 35 view of Fig. 1. Fig. 3, a view partly in section and partly in side elevation of certain details, Fig. 4 is a part of a top view of Fig. 3, partly in section, Fig. 5 shows a section on the line 5-5 of Fig. 3 as seen 45 from the left, and Fig. 6 is a section on the line 6-6 of Fig. 3 as seen from the right.

The gun A is mounted to slide on the slide carrier B, which extends considerably to the rear of the breech end a^1 of the gun 50 when in firing position, as shown; and the slide carrier is at its rear end provided with horizontal trunnions b^1 . By means of these trunnions the slide carrier is mounted in the top carriage C which can be turned 55 around the axis of a vertical pivot c^1 rela-

tive to the trail body D. Between the trail body D and the top carriage C is inserted a training gear, not shown in the drawing, which may be constructed in well known manner.

The elevating gear consists of two upwardly extending toothed segments C^2 carried by the top carriage C. In mesh with the toothed segments C^2 are pinions E secured on a shaft E^1 mounted in bearings on the slide carrier B. A hand wheel F, Fig. 2, is provided for operating the shaft E^1 . This hand wheel is mounted in a housing b^2 seated on one of the horizontal trunnions b^1 and is in gearing connection with the shaft E^1 by means of a pair of bevel wheels J inclosed in the housing b^2 , a shaft G and a worm gearing H H^1 , see Fig. 1.

For the recoil brake attached to a lug a^2 of the gun barrel, see Fig. 1, is provided in a well known manner a device which permits a shorter recoil of the gun barrel at high elevation than at low elevation. The length of the recoil at high elevation is moreover selected so that the recoiling parts do not enter between the walls of the trail body D with the top carriage C in the middle position; compare the position in dot and dash lines of the gun breech a^1 in Fig. 1.

The recoil brake cylinder K, Fig. 3, is rigidly attached to the lug a^2 of the gun barrel A. The rod l^1 of the recoil piston L carries a muff M secured thereon at its forward end, and which by means of a bayonet lock, is connected with the cap b^2 of the cradle B, so that the rod may turn but not shift lengthwise. The recoil cylinder, being broken off on the drawing almost entirely, reaches with the gun in firing position, nearly out to the muff M. A revolving sleeve N which may turn but not shift lengthwise is mounted on the piston rod l^1 and has orifices n^1 for the passing of the braking fluid. Said part N lies immediately against the piston-head L also provided with openings l^2 . The sleeve N has lugs n^2 running in the helical grooves k^1 , Fig. 3, of the recoil cylinder K. The grooves are laid out so that the sleeve N is turned in the direction of the arrow x , Fig. 5, when the brake cylinder recoils.

The muff M has an L-shaped extension m^1 m^2 , the arm m^2 of which is parallel to the axis of the piston rod and is provided with a stud m^3 at its free end. The stud m^3

engages in the groove σ^1 of the slide σ , which is placed inside of the cradle B and can travel in a guide P of the cradle, see Fig. 3, parallel with the axis of the piston rod P . The groove σ^1 runs obliquely to the axis of the piston rod P and in such a way that the piston rod is turned in the opposite direction of the arrow x , Fig. 5, through the parts M m^1 m^2 m^3 when the slide O is drawn to the rear from its position indicated in Fig. 1. At its rear end the slide O carries an arm σ^2 in which is secured a bolt Q , Figs. 3 and 4. This bolt Q reaches through a slot b^3 in the cradle B . The outer end of the bolt Q engages with the end of a link R which by means of a bolt S is pivotally connected to one of the toothed segments C^2 of the elevating gear. With the gun in horizontal position, the parts of the brake assume a relative position as shown in Fig. 3. The piston head L , relative to the sleeve N , will have such a position that its orifices t^2 coincide with the openings n^1 of the sleeve N . If the gun is elevated, the link R will swing around the axis of the bolt S . As a consequence of this, the bolt Q , during the elevation, will travel rearward in the slot b^3 and drag with it the slide O , which by means of the groove σ^1 engaging the stud m^3 , revolves the piston rod P and the piston head L in the direction opposite the arrow x , Fig. 5. Through this the passages n^1 of the sleeve N are partly covered by the piston head L , so that the gun barrel does not recoil as far as the plane in which the upper walls of the trail sides are situated, and the gun may, consequently be given extraordinarily great training in azimuth. The described gun mount possesses furthermore a simple construction and is directly after unlimbering in condition for firing and at the end of the firing immediately ready for travel.

I claim:

1. In a wheeled carriage for a recoil gun, having a trail; a top carriage with vertical pivot mounted to rotate on said trail, a

slide carrier on which the gun is mounted to recoil, an extension on said slide carrier to the rear of the gun breech, a pair of horizontal trunnions at the rear end of said extension and bearings for said trunnions on the rear end of said top carriage; an elevating gear for elevating said slide carrier with the gun around the axis of said trunnions, said elevating gear comprising an upwardly extending toothed sector carried by the forward end of said top carriage, a pinion in mesh therewith, revolubly mounted on said slide carrier, and driving means for said pinion; a recoil brake for the gun constructed to automatically diminish the length of the recoil when the gun barrel is elevated so that the gun breech cannot strike against the trail sides in any elevation of the gun.

2. In a wheeled carriage for a recoil gun, having a trail; a top carriage with vertical pivot mounted to rotate on said trail, a slide carrier on which the gun is mounted to recoil, an extension on said slide carrier to the rear of the gun breech, a pair of horizontal trunnions at the rear end of said extension and bearings for said trunnions on the rear end of said top carriage; an elevating gear for elevating said slide carrier with the gun around the axis of said trunnions, said elevating gear comprising a toothed sector on said top carriage, a pinion in mesh therewith, revolubly mounted on said slide carrier, a worm gear actuating said pinion, bevel gears and a hand wheel for training said worm and mounted on one of said trunnions; a recoil brake for the gun constructed to automatically adjust the length of the recoil when the elevation of the gun barrel is changed so that the gun breech cannot strike against the trail sides in any elevation of the gun.

The foregoing specification signed at Bar-
men, Germany, this 12th day of June, 1913.

NORBERT KOCH, [s.s.]
